Watson E. Coleman ATTORNEY.

UNITED STATES PATENT OFFICE.

BLESSIE E. AKERS, OF THRIFT, TEXAS.

BABY NET FRAME.

1,418,608.

Specification of Letters Patent. Patented June 6, 1922.

Application filed March 12, 1921. Serial No. 451,860.

To all whom it may concern:

Be it known that BLESSIE E. AKERS, a citizen of the United States, residing at Thrift, in the county of Wichita and State of Texas, has invented certain new and useful Improvements in Baby Net Frames, of which the following is a specification, reference being had to the accompanying drawings.

- 10 This invention relates to baby net frames and has for its object to provide a device of this character capable of holding the net in spaced relation to the bed or support on which it is placed.
- 15 Another object is to provide a device of this character capable of being readily folded when not in use and stored in a small space.
- 20 A still further object of the invention is to provide a device of this character wherein in the various parts of the device are held rigid when the frame is extended and in use, accidental folding being impossible.
- 25 A still further object of the invention is to provide a device of this character including a hub member to which a plurality of ribs are connected, said hub member being provided with a single means whereby all of the ribs are held stationary.
- 30 With the above and other objects in view, the invention consists in the improved construction and arrangement of parts to be hereinafter more particularly described, fully claimed and illustrated in the accompanying drawings, in which:
- 35 Figure 1 is a top plan view of a mosquito net frame constructed in accordance with an embodiment of the invention,

Figure 2 is a sectional view taken on the line 2—2 of Figure 1,

40 Figure 3 is a view in elevation of the hub member, the ribs being removed,

Figure 4 is a fragmentary view showing the connection of the braces to the ribs of the frame, and

45 Figure 5 is a detail perspective view of the brake joint brace.

Referring to the drawings, 5 designates a hub member stamped from metal, and including an annular flange 6 and a centrally projecting boss 7 by means of which the device may be readily handled. The upper surface of the hub member 5 is provided with a plurality of radiating channels 9 which extend from the periphery of the boss 7 to the flange 6. Formed in the flange 6

at the end of each of the channels 9 is a recess 10, while extending around the flange 6 is a groove 11 adapted to receive a pintle or wire 12. By the formation of the recesses 10, the portion of the wire 12 passing over the recesses is disposed in spaced relation to the end wall of the recesses and channels 9.

Connected to the hub member, is a plurality of ribs 13, each rib having its end portion 13^a sloping downwardly and cooperating with the adjacent ribs to form a dome. The end portion 14 of each rib is provided with an eye 15 by means of which the ribs are pivoted to the wire 12. It will be noted that the eye 15 is disposed in spaced relation to the extremity of the end 14 so that the end 14 is permitted at certain times to lie within the channel 9. By this novel pivotal connection, the ribs are permitted to be readily folded as the recesses 10 prevent contact of the eyes 15 with the hub member. The ribs are also positioned so that they radiate from the hub member 5.

The extremity of the ends 13^a are connected by means of a fabric strip 16 which forms the base of the frame and permits the ribs to be readily folded. It is obvious that the ribs 13 may readily swing towards the hub member when not in use so as to render the frame compact. When it is desired to hold the frame in its extended position, the ribs are firmly secured by means of a clamping plate 18 having a central opening 19 adapted to receive the boss 7. After the ends 14 of the ribs are disposed in the channels 9, the plate 18 is applied and engages the upper surface of the hub member 5 thereby locking the ends 14 within the channels. To prevent disengagement of the clamping plate, a plurality of locking fingers 20 are pivoted to the boss 7 and adapted to be swung over into engagement with the upper surface of the clamping plate 18 to force the plate into engagement with the upper surface of the hub member. It will be readily seen that with this clamping plate in position, it is impossible for the ribs 13 to accidentally fold and at the same time the frame is rendered substantial.

In order to hold the outer portion of the ribs in the desired position, there is provided a plurality of brake joint braces 21, each brace consisting of a rod 22 having a bifurcated end 23 and a lug 24 projecting from its opposite end. This lug is adapted

to be received in a recess 25 provided in the bar 26 of the brace, the side portion 27 of the recess being closed so as to limit movement of the brake joint of the brace 5 in one direction and hold the ribs extended. The opposite end 28 of the rod 26 is bifurcated as at 29. Each of the bifurcated portions 29 and 23 of the brace are adapted to be pivoted to an enlarged portion 30 formed 10 in each of the ribs 13.

By this novel arrangement, when the brake joint portion of each brace is moved toward the hub member it serves to spread the ribs and the fabric strip 16 so as to hold 15 the frame in the proper position. In addition to this the braces serve as supports to prevent the mosquito netting or cloth supported by the frame from sagging or falling between the ribs.

20 When it is desired to fold the frame, the locking fingers 20 are disengaged from the clamping plate 18 to permit the plate to be removed from the hub member and the boss 7 thereof. The brake joint portion of each 25 brace formed by the lug 24 and recess 25 is moved away from the hub member to cause the rods 22 and 26 to move toward each other together with the ribs so as to facilitate folding of the frame. The frame is thereby 30 rendered compact.

From the foregoing it will be readily seen that this invention provides a novel form of mosquito net frame which holds the mosquito net the desired distance from the bed 35 and occupant so that there is no chance of the hands of the occupant of the bed becoming entangled in the netting. At the same time, it holds the net in such a position that it is impossible for insects to enter 40 the dome formed by the frame. All of these features are possessed by a device that is simple in construction.

What is claimed is:—

1. A device of the character described 45 comprising an annular hub member, a boss projecting from the intermediate portion of

said member, the upper surface of said member being provided with a plurality of radiating channels, said channels extending from the periphery of the boss to the periphery of the hub member, said hub member having a recess at the outer end of each channel and having an annular groove in the periphery of said hub member, a wire disposed in said groove and extending across the recesses at the ends of the channels, a plurality of ribs, each of said ribs having one end portion thereof arranged to extend into one of the channels and having an eye 60 adapted to receive a portion of the wire disposed in the groove of the hub member, and means for holding the adjacent end portions of the ribs in the channel in the upper face of the hub member.

2. A device of the character described 65 comprising an annular hub member, a boss projecting from the intermediate portion of said member, the upper surface of said member being provided with a plurality of radiating channels, said channels extending 70 from the periphery of the boss to the periphery of the hub member, said hub member having a recess at the outer end of each channel, and having an annular groove in the periphery of said hub member, a wire 75 disposed in said groove and extending across the recesses at the ends of the channels, a plurality of ribs, each of said ribs having one end portion thereof arranged to extend into one of the channels and having an 80 eye adapted to receive a portion of the wire disposed in the groove of the hub member, and a ring adapted to extend over the boss and to engage the upper surface of the hub member to retain the adjacent ends of the 85 ribs within the channels, and means carried by the boss for holding said ring in engagement with the hub member and boss.

In testimony whereof I hereunto affix my signature.

MRS. BLESSIE E. AKERS.
